CROSBY FIELD, OF YONKERS, NEW YORK, ASSIGNOR TO NATIONAL ANILINE & CHEMICAL CO., INC., OF NEW YORK, N. Y., A CORPORATION OF NEW YORK

KEG-IMPREGNATING DEVICE, ETC.

Application filed August 29, 1923. Serial No. 659,869.

This invention relates to an impregnated keg or other similar wooden container which is intended to be used for the transportation or storage of various products which are injured by the loss of their moisture content to the atmosphere through the walls of the container, or by the absorption of moisture from the atmosphere through these walls.

The deterioration or loss of various chemical products by reason of leakage through the walls of the container presents a serious problem, especially when the materials are to be transported for great distances, and it has been common practice hitherto to make use of a container which has been treated with various substances which are intended to prevent such leakage. One form of container used for this purpose consists of a keg, the staves and heads of which have been immersed in an inert material, usually heated, and the impregnation takes place throughout the surfaces of the container and the impregnating material enters to a considerable depth into the wood. Such a container as this, however, is not altogether satisfactory, as it is found that this complete impregnation makes the wooden parts more or less brittle and the keg does not stand up in service. Also if the parts are treated prior to their assembly, then the staves are not bound together and leakage may occur between the edges of the staves and also between the staves and edges of the heads.

Another method by which attempts have been made to solve the problem consists in introducing a coating material such as paraffin into the keg through the bung hole, closing the bung and rocking or manipulating the keg so as to bring the molten paraffin into contact with all of the inner surfaces. The bung is then removed and the surplus liquid drained off. By this method the entire inner surface of the keg is coated with a layer of inert material, but it is found that such a coating is likely to chip or flake off in service. This is perhaps due to the fact that the pores of the wood are filled with air and the paraffin spreading over the surface seals the air in the pores. This confined air, expanding and contracting upon temperature changes,

serves to loosen the paraffin lining and cause it to chip off in spots. It is possible, also, that this confined air forms a thin film between the paraffin and the wood fibre, which prevents a perfect adherence of the paraffin to the wood. In any event, containers so treated are not altogether satisfactory since the lining soon permits leakage. It is also true that in such treatment it is impossible to provide a uniform paraffin coating, and the paraffin may accumulate in the form of small blocks or cakes which are readily torn loose upon relative movement of the staves, such as is likely to occur in handling. The breaking loose of particles of the coating not only makes an imperfect lining, but the loosened material enters the contents of the keg and in many cases this is a detrimental contamination.

The object of the present invention is to provide a keg which is impregnated in such a manner as to have a lining of inert material which is continuous and not easily chipped off, and also to provide a keg so impregnated as not to weaken the material forming the staves. Another object of the invention is to provide a process and apparatus by which such an impregnation process may be carried on with a minimum expenditure of the impregnating material.

In producing the new impregnated keg the first step in the process is the evacuation of the keg by means of a vacuum pump. With the vacuum maintained the molten paraffin is introduced into the keg and caused to cover all of the interior surfaces thereof. The evacuation serves to free the pores of the wood from air bubbles or to remove the air film, as the case may be, and the impregnating material is absorbed to a slight depth in these walls. After the impregnating material has been allowed to remain in contact with the walls for such a length of time as is found necessary to produce a product of the desired characteristics, it is allowed to flow out so as to leave a thin film or coating on the walls. The vacuum is then broken and the air rushing in from the atmosphere not only serves to cool and solidify this coating, but also exerts a force upon it, tending to

drive the coating into the walls. The film of paraffin so formed is not only continuous over the walls of the container, but enters the interstices between the staves. By varying the factors of time, vacuum, air pressure, temperature, and amount of paraffin, the coating is easily controlled and made suitable for the particular service desired. This impregnating film protects the product in the container and prevents the loss or absorption of moisture through the container walls but does not extend into these walls such a distance as would impair the strength of the wood. The keg then is substantially as strong as an untreated keg, since the great part of the thickness of the staves is in its original unimpregnated condition. Also the impregnating material is firmly bound in place and does not readily chip or flake. At the conclusion of the treatment the excess of impregnating material, which is still molten, is recovered and returned to a suitable vat or tank from which it may again be withdrawn as desired.

15 One form of apparatus by which the process, above briefly described, may be carried on is illustrated in the form in which it is at present preferred in the accompanying drawings, in which

20 Fig. 1 is a vertical cross-section showing a keg in position in the apparatus, the keg being shown partially in elevation,

25 Fig. 2 is a diagrammatic elevation showing the complete lay-out,

30 Fig. 3 is a cross-sectional view on the line 3—3 of Fig. 1, and

35 Fig. 4 is a cross-sectional view on the line 4—4 of Fig. 1.

40 In these drawings there is shown a vessel 5, provided with hollow trunnions 6, 6 extending from the outer walls thereof. This vessel may be of any desired material but is preferably constructed of metal, such as iron or steel, provided with a layer of heat insulating material 7.

45 The vessel is supported on the trunnions 6, 6 in suitable bearings 8, 8 supported on legs 9, 9 in any convenient location. At its upper end the vessel is provided with a cover 10, hinged as at 11, which may be locked in place by means of a quick-acting latch 12, hinged on the wall of the vessel at a point opposite the cover hinge. The rim of the vessel is provided with a channeled member 13 in 55 which is mounted a packing ring 14 by means of which the cover may be sealed so as to make an air-tight joint with the end of the vessel. On its inner face the cover is provided with guide flanges 15 which serve to 60 center and hold in position the keg 16 which is to be treated. The inner walls of the vessel are also provided with guide members 17, secured to the walls in any desired manner and shaped to conform to the shape of the 65 keg.

70 Welded or otherwise secured to the inner walls of the vessel in any desired manner is a head 18, this head being spaced inwardly from the lower end of the vessel so as to form a chamber 19 having a capacity equal to or preferably greater than the capacity of the keg. This head has a plurality of supports 20 extending upwardly from its upper surface, the supports being so arranged that the ends of the keg staves will rest upon them so as to support the keg. The head is also provided with a plurality of spaced apertures 21. The head is also formed with a somewhat arcuate aperture 22. Located centrally of the head and mounted on the upper face of the head so as to partially overlie this aperture is a circular plate 23 having a central aperture through which extends a flanged sleeve member 24, this member having marginal flanges on either side of the head. Located in the upper flange 25 is a packing ring 26 and encircling the sleeve is a spring 27 which bears at one end against the plate 23 and at the other against the inner face of the flange 25. As will be seen in Fig. 1, when a keg 16 is placed in position to rest on the supports 20 with its bung 28 downward, the sleeve 24 will be forced upward by means of its spring to force the gasket 26 against the head, so that the keg is resiliently held against the cover.

75 It will be noted that one of the hollow trunnions 6 is in communication with the interior of the vessel through an aperture 29, formed in the side wall thereof and the end of this trunnion is closed by a cap 30, provided with a gasket 31 through which extends a pipe 32 which forms part of the vacuum line. As will be seen in Fig. 2, this pipe 32 is provided with a gauge 33, and a valve 34 and is connected to a receiver 35 which is also in communication with the vacuum pump. The other trunnion is provided with a similar cap and gasket 30, 31, and through this cap extends the end of a pipe 36, the lower end of which enters a vessel 37 in which the impregnating material is to be heated. Referring particularly to Fig. 2, it will be noted that this vessel is provided with a steam coil 38 and with a float 39 having an indicating rod 40 extending upwardly therefrom and serving to indicate the level of the liquid in the tank on a scale 41 located at a convenient point near the trunnions. There is a valve 42 in the line 36 so that the flow of liquid through this line may be controlled. Extending downwardly from the trunnion 6, which is in communication with the line 36, is a pipe 43, provided with a **T** 44 to which is connected a nipple 45, extending through the wall of the vessel and connected by suitable fittings to a **T** 46, connected with a nipple 47 extending downwardly and a long nipple 48 extending upwardly therefrom, the upper nipple being of sufficient length to extend 80 85 90 95 100 105 110 115 120 125 130

through the sleeve 24 and enter the keg through the bung hole. The various threaded connections, by means of which the nipple 48 is connected to the nipple 45, permit of a 5 certain freedom of movement in the position taken by the nipple so that in case the bung hole in the keg is not exactly centered the sleeve may be moved in the arcuate aperture 22 in the head 18, and the nipple may also be 10 swung so as to take the position necessary for it to enter the bung hole. This freedom of movement is illustrated in Fig. 4.

At the lower end the vessel is provided with a domed head 49 at the bottom of which is 15 an aperture 50 encircled by a channeled flange 51, in which is mounted a gasket 52 and overlying this aperture is a flap door 53, hinged at 54 to the end wall. Mounted in any desired manner below the vessel, as is shown 20 in Fig. 2, is a conical tank 55 provided in its lower end with a screen 56 and an outlet 57, this outlet directing the contents of the tank into the heated tank 37.

The vessel is also provided with an up- 25 standing handle 58, by means of which it may be rocked on its trunnions for a purpose later to be described.

In operation the keg 16 is placed in the position shown in Fig. 1, with the nipple 48 ex- 30 tending through the bung hole and the keg properly centered by the guides 15 and 17. The cover 10 is then closed and locked in position. The vessel is now rotated on its trunnions so as to place the keg with its longi- 35 tudinal axis vertical, with the bung hole up, and the flap door closed by gravity. The valve in the paraffin line is now closed and the vessel placed in communication with the vacuum line by opening the valve 34. This 40 exhausts the interior of the vessel and the keg and is carried on until the desired degree of vacuum is indicated on the gauge 33. The vacuum line is then closed, the paraffin line opened and a quantity of paraffin admitted to 45 the keg sufficient to fill it, this amount being indicated by the float moving the rod 40 over the scale 41. After the desired amount of paraffin has flowed into the keg the paraffin line is closed and the keg rocked to the 50 reverse position, as is shown in Fig. 1, with the bung hole down. The paraffin then flows out into the chamber 19 below the head 18 and in doing so a thin film of paraffin is left 55 on the inner walls of the keg. The vacuum is now broken and this film is immediately solidified and forced into the walls of the keg by atmospheric pressure. Upon the breaking of the vacuum the flapper valve 53 immediately opens, since it has been held in position only by the vacuum, and the paraffin 60 flows out into the conical tank 55, thence through the screen and to the heated tank. From time to time additional paraffin is placed in the heated tank as may be desired. 65 Upon the removal of the excess paraffin the

vessel is rotated to any desired position, the latch unlocked, the cover opened and the keg is then removed and a new one inserted.

It will be seen that by this process the keg is impregnated to a slight depth which may be governed by the degree of exhaustion and the length of time the paraffin is allowed to remain in contact with the walls of the keg. Only a thin film of paraffin is coated over the staves but this coating is continuous not only over the staves but across the seams between them. The expenditure of paraffin is, therefore, relatively small and the coating operation is carried on with great rapidity. It has been found that a coating applied by 75 this new process is not only uniform, but also firmly bound in place so that it has no tendency to chip off so that leakage may occur.

While the new container has been illustrated and described in the form of a wood keg impregnated with paraffin as the inert material, it will be seen that various other forms of container may be produced with equal facility, and that other impregnating material may also be used. The process of treatment for the production of such containers, however, remains substantially the same, regardless of the shape and form of the container, the material of which it is made, 80 and the material with which it is impregnated.

I claim:

1. A process for partially impregnating the walls of a container which comprises sub- 100 mitting the container to a vacuum, introducing a liquid impregnating medium into the container while maintaining the vacuum, withdrawing the excess medium to leave a film thereof over the walls of the container 105 and thereafter breaking the vacuum while the material in the film is still in a liquid condition.

2. A process for partially impregnating the walls of a container which comprises sub- 110 mitting the container to a vacuum, filling the container with a liquid impregnating medium, allowing the medium to drain from the container to leave a thin film of the medium on the walls thereof and then breaking the vacuum while the material in the film is still liquid.

3. A process for partially impregnating the walls of a container which comprises placing the container in a closed chamber, 120 exhausting the chamber and container, introducing a liquid impregnating medium into the container while maintaining the vacuum, allowing the excess liquid material to drain from the container into the chamber to leave a thin film of the medium on the inner walls 125 of the container and then breaking the vacuum to solidify this film.

4. A process for partially impregnating the walls of a container which comprises 130

placing the container in a closed chamber, exhausting the chamber and container, introducing molten paraffin into the container while maintaining the vacuum, allowing the excess paraffin to drain from the container into the chamber to leave a thin film of paraffin on the inner walls of the container and then breaking the vacuum to solidify this film.

5 10 5. Apparatus for partially impregnating the walls of a container which comprises a vessel, a support for a container within the vessel, means for sealing the vessel, means for exhausting the vessel, means for introducing a liquid impregnating medium into the container while the vacuum is maintained, and an outlet in the vessel for the removal of the impregnating medium.

15 20 6. Apparatus for partially impregnating the walls of a container which comprises a vessel, resilient means for supporting a container therein, means for exhausting the vessel and container, means for introducing an impregnating liquid into the container while the vacuum is maintained, and a compartment in the vessel adapted to receive the liquid introduced into the container.

25 30 7. Apparatus for partially impregnating the walls of a container which comprises a rotatably mounted vessel, provided with an air-tight closure at one end, a resilient support within the vessel for a container, a compartment in the other end of the vessel, a closure for the compartment, means for exhausting the vessel and container and means for introducing an impregnating liquid into the container through the compartment while maintaining the vacuum.

40 45 8. Apparatus for partially impregnating the walls of a container which comprises a vessel having an air-tight closure at one end, a head in the vessel providing a compartment in the other end thereof, means mounted in the head for resiliently supporting a container against the closure, means for exhausting the vessel and container, means for introducing an impregnating liquid into the container and an outlet communicating with the compartment.

50 55 9. Apparatus for partially impregnating the walls of a container which comprises a vessel provided with a closure at one end and an apertured head within the vessel forming a compartment in the other end, means for resiliently supporting a container within the vessel, a vacuum pump communicating with the vessel through valved connections, a source of supply of impregnating liquid communicating with the vessel, and an outlet for the liquid from a compartment.

60 65 10. Apparatus for partially impregnating the walls of a container which comprises a vessel, a support for a container therein, means for sealing the vessel, a vacuum pump in communication with the vessel, a supply

of impregnating material, connections for introducing this material into the container while a vacuum is maintained therein and means for indicating the quantity of impregnating material so introduced.

70 11. Apparatus for partially impregnating the walls of a container which comprises a vessel provided with a head forming a compartment in communication with the main body of the vessel, means for supporting a container within the vessel, a vacuum pump in communication with the vessel, means for regulating the exhaustion of the vessel and container, a supply of impregnating material, means for introducing such material into the container while the vacuum is maintained and means for indicating the amount of material so introduced.
